UNITED STATES PATENT OFFICE

WILLIAM B. TATRO, OF HARTFORD, CONNECTICUT.

PIPE-GRIPE.

SPECIFICATION forming part of Letters Patent No. 252,632, dated January 24, 1882.

Application filed October 31, 1881. (No model.)

To all whom it may concern:

Be it known that I, WILLIAM B. TATRO, of Hartford, county of Hartford, and State of Connecticut, have invented certain new and useful Improvements in Pipe-Gripes, of which the following is a full, clear, and exact description, reference being had to the accompanying drawings, and to the letters of reference marked theron.

10 My invention has relation to that class of devices or implements called "pipe gripes," and intended to be applied to the jaws of any ordinary bench-vise for the purpose of holding a pipe or rod or similar article to be cut or worked, 15 thus converting the vise for the time into a pipe-holding vise.

10 The object of my invention is to produce a simple, cheap, and substantial implement, which may be readily attached to and detached from 20 the jaws of the vise, wherein the tooth-pieces are made separate from and afterward applied upon the faces of the jaws of the pipe-gripe, wherein the back plate and front plate of the pipe-gripe are prevented from separating from 25 each other by attachments applied at their margins, instead of at their centers, as in previous constructions, and wherein the adjacent surfaces of these plates (when in use) are so formed as to afford an extended and secure 30 bearing, obviating all danger of breaking by extreme pressures.

To this end my improvements involve certain novel and useful peculiarities of construction and arrangements or combinations of parts, 35 all of which will be herein first fully described, and then pointed out in the claims.

In the accompanying drawings, forming part of this specification, Figure 1 is a perspective view of a pipe-gripe constructed and arranged 40 in accordance with my invention. Fig. 2 is a vertical section and elevation upon a plane passing through one of the jaws. Fig. 3 is a side elevation of one of the jaws, showing a modified manner of locating the coupling-strips 45 thereon, the back plate being omitted. Fig. 4 is a perspective view of one of the tooth-pieces detached from its seat in the face of the jaw.

In all these figures like letters of reference, wherever they occur, indicate corresponding 50 parts.

Pipe-gripes of this character are ordinarily constructed or composed of two main parts, one for each of the jaws of the vise, and one part has a single jaw made to enter the space between the two jaws on the opposite part. The pipe 55 or other article to be held is clamped between the two parts, as is well understood.

A is the back plate, intended to be secured against the face of the vise-jaw, and for this purpose it is provided with a tang, B, having 60 setting-screw C, for bearing upon the top of the vise-jaw, and with nibs D D or other suitable projections, which fall beneath the vise-jaw. Other approved means of securing the gripe upon the vise may, however, be adopted. 65

E is a jaw of the pipe-gripe, mounted upon back plate, A, and recessed in front, substantially as indicated, for the accommodation of the pipe or rod to be held. The gripping-teeth are made upon a piece separate from the jaw 70 and afterward applied and held in place.

Heretofore in this class of pipe-gripes the jaw has been made of cast-steel throughout, and of other metal, teeth and all, and on account of its form and size has been liable to crack and 75 break, destroying the whole implement.

I make the teeth upon a separate piece of steel, as F. This should be of good quality and well made. It is preferably of bar-steel, the teeth being cut or milled thereon after the bar 80 is bent to fit the recess in the jaw. It may be otherwise made, however, as by drop-forging or other well-known means, and tool-steel is found to be the best material for the purpose. This tooth-piece F is made to fit a narrow 85 groove in the front of the jaw, and is held in place at top and bottom by the overlapping ends a a of the strips G, employed also for coupling the face and back plates together. The jaws and the plates may be made of ordinary 90 cast or malleable iron or other metal, and then, with the separate steel tooth-pieces in place, form an implement of superior durability and less cost than the ordinary forms above alluded to. The tooth-pieces F may be readily detached 95 by simply taking off one of the holding-strips G, and they may then be replaced by new ones, if desired. This removability of the tooth-pieces might be secured by use of screws passing through them and entering the jaws; but I pre- 100

fer the construction shown, as it enables me to make the pieces F of lighter material than would other wise be required.

The jaw E is cast with the face plate, H, and the strips G have tongues b, which ride over the margin of the back plate, A, serving to couple the parts together. The back plate, A, is slightly dished, as indicated, and the face plate, H, is inclined, so as to fit fairly and smoothly into the hollow so formed. A central stud, K, on the face plate enters a recess formed in the back plate for its reception, and around the stud the material of the face plate may be removed, as shown at c.

When the pipe-gripe is in use the stud K does not quite reach the back plate and the recess c prevents the possibility of the two plates being brought into contact at their central parts. Any strain upon the gripe so constructed will be transmitted to the part of the back plate removed from the center, and thus all liability to break the face plate is obviated.

A central bearing, such as heretofore employed in this class of devices, admits of the outer portions of the face plate being bent over the center as over a fulcrum, which bending renders the plate liable to be broken. By coupling the plates at the margin, instead of at the center, any tendency to crowd one out of position will be counteracted by the coupling to much greater advantage, the holding power having a leverage over the crowding strain equal to the diameter of the face plate, instead of only the radius; and the adoption of the inclined bearing surfaces between the back and face plates enables me to make the gripe more compact than heretofore, because such heavy weight of material is not required to withstand the strains brought upon it. Inasmuch as these grips are to be placed between the jaws of the vise, one part upon each jaw, this compactness is of material advantage, especially when the limit of movement of the vise-jaws is restricted, as it is in many forms of vises. If the bearing-surfaces of these two plates were made plain or flat, as heretofore, in order to obtain the required strength, the back plate would necessarily be thicker in the center than herein shown, and the front plate thicker at the periphery, thus employing more metal and causing the gripe to occupy a greater space between the jaws of the vise. Moreover, the correspondingly-inclined bearing-surfaces resist any tendency to sidewise displacement of the two plates when in use, obviating the necessity of a headed central pin passing through the back plate, as heretofore.

The stud K prevents overcrowding against the coupling-strips and helps to maintain the parts in their proper relative positions. It may be formed upon the back plate, if desired, and enter a recess in the adjacent plate. The holding-strips may be set in recesses provided for them, as in Fig. 3, instead of being located along the tops of the jaws, as in Figs. 1 and 2. Ordinary screws are employed to hold the

coupling-strips in place; but other means of attachment may be adopted. The part of the gripe having the two jaws has also double sets of holding-strips and removable tooth-pieces. In other respects it is constructed the same as the part having the single jaw.

The improved device, constructed and arranged substantially as herein indicated, is easily and cheaply made, not liable to damage either in the manufacture or ordinary use, and answers the purposes or object of the invention, as previously stated. When the teeth become worn they can be quickly replaced by a new set—an advantage not attained in former constructions.

Having now fully described my invention, I will add that I do not claim broadly a pipe-gripe to be applied to the jaws of a vise, nor such a pipe-gripe having revolving jaws; but

What I do claim as new, and desire to secure by Letters Patent, is—

1. In a pipe-gripe composed of two main parts for attachment to the separate jaws of a vise, the combination of the back plate and the recessed jaw provided with the removable tooth-plate, said jaw being loosely secured to the back plate by coupling-strips extending over the margin of the back plate, substantially as and for the purposes set forth.

2. In a pipe-gripe composed of two main parts for attachment to the separate jaws of a vise, the combination of the back plate, the front or jaw plate, the jaw formed thereon, the separable tooth-plate, and the coupling-strips, serving to hold the several parts substantially in the manner shown and described.

3. The recessed jaw formed upon the face plate and grooved in its front edge and the separate steel tooth-plate bent to correspond with the recessed jaw and fitting the groove therein, said jaw being mounted and arranged upon a back plate, the several parts being held in place by coupling-strips which extend over the margin of the back plate, substantially as shown and described.

4. In a pipe-gripe of the character herein set forth, the face and back plates correspondingly inclined on their bearing-surfaces, substantially as and for the purposes set forth.

5. In a pipe-gripe, the combination of the back plate and the face plate bearing the jaw or jaws, the two plates being coupled at their margins, substantially as set forth.

6. In a pipe-gripe, the two plates, made movable one upon the other, coupled at their margins and provided with a centrally-disposed stud, substantially as shown, and for the purposes set forth.

In testimony that I claim the foregoing I have hereunto set my hand in the presence of two witnesses.

WM. B. TATRO.
